US0D1079253S

(12) United States Design Patent (10) Patent No.: US D1,079,253 S
(45) Date of Patent: * Jun. 17, 2025

(54) CARD WALLET

(71) Applicant: RGA SUNSHINE, Austin, TX (US)

(72) Inventor: Samuel Bodner, Berlin (DE)

() Term: 15 Years

(21) Appl. No.: 35/517,985

(22) Filed: Jul. 20, 2023

(80) Hague Agreement Data

Int. Filing Date: Jul. 20, 2023

Int. Reg. No.: DM/230458

Int. Reg. Date: Jul. 20, 2023

Int. Reg. Pub. Date: Aug. 4, 2023

(51) LOC (15) Cl. 03-01

(52) U.S. Cl.

USPC D3/247

(58) Field of Classification Search

USPC D3/201, 227, 247, 248, 249, 250, 302, D3/303; D6/314; D8/355; D14/420,
